UNITED STATES PATENT OFFICE.

FRED NEWELL TILTON, OF HARTFORD, CONNECTICUT.

SCREW THREADER AND POINTER.

1,252,630.

Specification of Letters Patent.

Patented Jan. 8, 1918.

Application filed August 1, 1914, Serial No. 854,513. Renewed September 21, 1917. Serial No. 192,628.

To all whom it may concern:

Be it known that I, FRED N. TILTON, a citizen of the United States, residing at Hartford, in the county of Hartford and State of Connecticut, have invented a new and useful Improvement in Screw Threaders and Pointers, of which the following is a specification.

This invention relates to the mechanism in a screw forming machine which controls the operation of the tool for cutting the threads upon the blanks. As the invention is particularly applicable to the mechanism which affects the movements of the tool for threading and pointing gimlet pointed wood screws it is illustrated and described herein as embodied in a wood screw machine.

In machines for threading and pointing gimlet pointed wood screws the blanks are fed one at a time to a guide and driver and while rotated by the driver are subjected to the action of a tool which is so fed as to cut the required threads. This tool is repeatedly fed along the blank from the shank to the point and returned, each time making a deeper cut. To accomplish these cuts there is a lead cam which is designed to advance the tool at a speed which determines the pitch of the thread and a distance which depends upon the length of the screw; a form or depth cutting cam which through the form plate increases the depth of each cut until the thread is completed; a return cam which acts so that the tool will be drawn away from the blank during its return movement; and a holder cam which acts so as to allow the tool to be held out while the blanks are being fed into the guide and engaged by the driver which causes their rotation; all of these parts being combined with the necessary actuating and connecting mechanisms which cause them to automatically control the movements of the cutting tool to effect the desired result.

The object of this invention is to provide a machine of this character with means whereby the tool, at each successive advance during every cycle of the machine, as it approaches the tips of the blanks will not only cut deeper but will be carried in toward the axes of the blanks so as to form the necessary gimlet points at the ends of the screws, thus obviating the necessity of previously pointing the blanks in another machine as has heretofore been considered essential to the

successful production of high-grade wood screws.

This object is attained in a preferred manner by providing a pointing cam, and the necessary connections, which will slowly feed the controlling form in such manner that the tool each time it approaches the end of a blank not only makes a deeper cut for forming the thread but moves in so as to point the blank and form the desired thread on the pointed end.

As the blank feeding, rotating, guiding and releasing mechanisms form no part of the present invention, and may be any of the types in common use, they are not illustrated and described herein, only so much of a wood screw machine being set forth as is necessary to a complete comprehension of the preferred embodiment of the invention. Figure 1 shows a front elevation of the tool actuating mechanism of the machine. Fig. 2 shows the drive gearing at the right hand end of the machine. Fig. 3 shows an elevation of the form feed or pointing cam and lever at the left hand end of the machine. Fig. 4 shows a plan of the pointing cam and lever. Fig. 5 shows a vertical section of the machine on the plane indicated by the dotted line 5—5 on Fig. 1. Fig. 6 shows a side elevation of the form, the form or depth cam which causes the tool to cut deeper at each successive feed, the holder cam which allows the tool to be held out when the blanks are being fed into cutting position, and the levers which provide the connections between these cams and the form. Fig. 7 is a section through the tool post on the plane indicated by the dotted line 7—7 on Fig. 1, showing a side elevation of the tool and its carrier, the tool post arm and part of the form plate and arm. Fig. 8 shows a plan of the form with one of the form plates used for controlling the action of the tool. Fig. 9 shows a side view of the return cam, the form and the lever which connects these parts. Fig. 10 shows a plan of the form and the lever attached to the form arbor which is actuated by the depth cam and holder cam.

The cutting tool 1 is adjustably fastened in a carrier 2 that is clamped on a tool post 3. This post is loosely supported so that it may be turned and also moved longitudinally in bearings in the standards 4 and 5 which extend upwardly from the bed 6 of

the machine illustrated. The tool post is moved in one direction for feeding the tool along from the shank to the point of the screw 7, by the lead cam 8 that is adjustably fastened to the front cam shaft 9, and the post is drawn in the opposite direction by the spring 10 which has one end fastened to the standard 11, that extends upwardly from the bed, and which has its other end fastened to an arm 12 that is clamped to the post. The spring 10 is fastened between these parts so that it not only holds the post back against the lead cam but tends to draw the arm in and turn the end of the cutting tool out from the screw blank. The lead cam is shaped and timed to advance the tool at such a speed that it will cut a thread of the desired pitch on the screw blank.

Clamped on the tool post is an arm 13. The lower and inner end of this arm is held against the form plate 14 by the pull of the spring 10 which draws back the tool post. This form plate varies in size and shape according to the size and shape of the screw which is to be formed and its front edge is curved forwardly at one end so that as the tool post is moved by the cam for causing the tool to cut, the arm 13 near the end of its movement is forced out and the tool is turned in toward the axis of the blank for forming the point of the screw. The form plate is attached to an arm 15 which is clamped to the form arbor 16 that in the machine illustrated is loosely mounted in bearings in the standards 4, 5 and 11. Clamped on the form arbor is a rearwardly extending lever 17. This lever bears a spring finger 18 with a plate 19 which is adjusted to the desired position by a screw 20. The plate 19 is held in contact with the depth cam 21 by the pull of a spring 22. The cam 21 is fastened on the back cam shaft 23. This cam is so shaped that through the lever 17 the arbor is turned and the form is swung in such manner that during every cycle of the machine, at each advance the tool will make a deeper cut in the blank. Fastened on the side of the depth cam 21 is the holder cam 24. This cam is adapted to engage the block 25, which is on one side of the lever 17, and hold the lever down with the form swung back so that the tool will be thrown out while during the operation of the machine a blank is, by any common feed mechanism, delivered into cutting position in the back guide 26 and is engaged by the driver 27 by means of which the blank is rotated, in the usual way in machines of this type.

Adjustably fastened on the front cam shaft 9 is the cam 28 which is adapted to engage the return cam lever 29 that is fastened to the form arbor 16. This cam is so timed that it rocks the lever, turns the arbor 65 and swings back the form so as to allow the

tool to swing out away from the blank each time it makes its return movement.

On the back cam shaft 23 is a cam 30 engaging with the face of which is the end of a spring finger 31 that is attached to a lever 32 and is adjusted to exact position by a screw 33. The other end of this lever is forked and engages between collars 34 on the arbor which carries the form. The form arbor 16 is drawn back and the lever is held 75 in contact with the pointing cam 30 by the spring 47 which is connected between the bed and the arbor. This cam 30 is so timed that through the lever it moves the arbor longitudinally and carries the form side- 80 wise so that at each successive advance of the tool the form arm 13 travels a little farther up on the curved end of the form plate. As a result of this the tool not only at each 85 advance makes a deeper cut but at the end of each advance is caused to cut away the tip of the blank so as to form the desired point of the screw.

Power for rotating the shafts and cams is applied to the driving pulley 35 which is 90 on one end of the drive shaft 36 that extends across the machine and at the other end has a drive pinion 37. The drive pinion meshes with an intermediate gear 38 which with its attached pinion 39 is mounted on a 95 bracket 40 that is adjustably fastened to the outer face of the standard 11. The pinion 39 engages with the gear 41 that is fastened on the front cam shaft 9. Attached to this gear is a pinion 42 which meshes with a second intermediate gear 43 that with its attached pinion 44 is mounted on a bracket 45 that is adjustably fastened to the outer face of the standard 11. The pinion 44 engages with a gear 46 that is fastened to the end of 100 the back cam shaft 23.

By means of the addition to the screw machines in common use of the simple pointing cam and lever for moving the form arbor as above described, the form, which controls the depth at which the tool cuts into the blank,—which permits the tool to return freely after each cut,—and which permits the tool to be held out while the blanks are being positioned, is actuated in 110 such manner that the tool will cut the thread and at the same time cut off the tip of the blank and form the desired gimlet point on the screw without necessitating the previous pointing of the blanks in a pointing 115 machine.

The invention claimed is:—

1. The combination in a screw machine of a tool, a lead cam for advancing the tool, a spring for returning the tool, a form for 125 controlling the movements of the tool, a depth cam actuating the form so as to regulate the depth of the tool cut, a pointing cam actuating the form so as to cause the tool to point the blank, and a return cam actuating 130

the form so as to allow the tool to withdraw from the blank when it is returned.

2. The combination in a screw machine of a tool, a lead cam for advancing the tool, a spring for returning the tool, a form for controlling the movements of the tool, a cam actuating the form for regulating the depth of the tool cut, a cam actuating the form for causing the tool to cut the point of the blank, 10 a cam actuating the form for causing the tool to be withdrawn from the blank during its return movement, and a cam actuating the form for holding the tool out while the blank is being located in position to be cut.
- 15 3. The combination in a screw machine of a tool, a cam for advancing the tool, an oscillatory and reciprocatory form for controlling the position of the point of the tool, a cam for swinging the form so that each 20 successive cut of the tool will be deeper than the preceding cut, and a cam for feeding the form longitudinally so that near the end of each advance the tool will cut deeper than at the same locality during the preceding cut for threading and pointing a screw.

- 25 4. The combination in a screw machine of a tool, a lead cam for advancing the tool, a spring for returning the tool and holding it away from the blank, an oscillatory and 30 reciprocatory form for turning the point of the tool toward the blank, a cam for swing-

ing the form so as to increase the depth of the successive cuts, and a cam for reciprocating the form so as to still more increase the depth of the successive cuts near the 35 end of each advance movement of the tool.

5. The combination in a screw machine of a tool, a form for controlling the cutting action of the tool, and two independent cams arranged to actuate the form, one of said 40 cams feeding the form transversely so as to regularly increase the depth of each tool cut, and the other of said cams feeding the form longitudinally so as to still further increase the depth of each tool cut near the 45 point of the blank.

6. The combination in a screw machine, of an oscillatory and reciprocatory form, a spring cam and lever for oscillating the form, and a spring, cam and lever for reciprocating the form.

7. The combination in a screw machine of an oscillatory and reciprocatory form, means for oscillating the form, and means for reciprocating the form, said form oscillating 55 and form reciprocating means being separate and acting independently of each other.
